Patented Apr. 30, 1918.

Inventor

D. W. SCHWIEGER

By *Watson E. Coleman*

Attorney

UNITED STATES PATENT OFFICE.

DOROTHEA W. SCHWIEGER, OF FARIBAULT, MINNESOTA.

PROTECTING DEVICE.

1,264,445.

Specification of Letters Patent. Patented Apr. 30, 1918.

Application filed February 26, 1917. Serial No. 151,034.

To all whom it may concern:

Be it known that I, DOROTHEA W. SCHWIEGER, a citizen of the United States, residing at Faribault, in the county of Rice and State 5 of Minnesota, have invented certain new and useful Improvements in Protecting Devices, of which the following is a specification, reference being had to the accompanying drawings.

10 This invention relates to an improved protecting device and has for its primary object to provide an article adapted for application to the thighs of the user to protect the same against cold, the device being 15 particularly advantageous for use by invalids or others having poor blood circulation.

It is a more particular object of the invention to provide a device for the above purpose including an inner lining preferably of flannel, an intermediate blanket and an outer casing or covering, said blanket being detachably connected at each of its ends to the outer casing, said casing having a draw string in one end to encircle the waist, 25 and additional means connected to the blanket whereby the device may be suspended from the shoulders.

30 It is a further general object of my invention to provide a device for the above purpose which is simple in its construction, may be easily kept in a thoroughly clean and sanitary condition, and is highly convenient and serviceable in practical use.

With the above and other objects in view, 35 my invention consists in the novel features of construction, combination and arrangement of parts to be hereinafter more fully described, claimed and illustrated in the accompanying drawing, in which,

40 Figure 1 is a perspective view illustrating the manner of application and use of my invention;

Fig. 2 is a vertical sectional view through the device;

45 Fig. 3 is a fragmentary elevation illustrating the manner of connecting the suspender straps to the blanket;

Fig. 4 is a detail view showing the manner of detachably connecting the blanket 50 at one of its ends to the inner lining and the outer case or cover.

Referring in detail to the drawing, 5 designates the inner flannel wall or lining of the device which contacts with the skin, said 55 lining being of circular form in plan and of

requisite size. This flannel lining sheet is provided upon its inner face and adjacent to its lower end with opposed pockets indicated at 6, which are adapted to receive a hot water bottle or other suitable heating 60 means.

To the upper end of the lining 5, the edge of an outer case or linen cover 7 is stitched, the stitching being omitted at spaced intervals to provide openings or slits 8 for a purpose which will be later explained. In this edge of the cover or case 7, a draw string 9 is arranged, whereby the upper end of the case and the lining sheet may be contracted about the waist of the user. 70

10 indicates a blanket having inner and outer walls stitched or otherwise permanently secured to each other at their ends, said blanket being of continuous circular form in plan and stuffed between the inner 75 and outer walls with down or goose feathers, as indicated at 11. The blanket at one end is provided with snap fasteners 12, whereby said end of the blanket can be partially closed, and the corresponding end of the outer cover sheet is provided with similar fasteners indicated at 13 for a like purpose. The case 7 is preferably provided with a ruffle 14 to give the article a finished appearance. 85

To the upper edge of the blank 10, at spaced intervals, the cord loops 15 are secured. Cords or tapes 16 are also secured to the upper edge of the lining sheet 5, each of said cords being suitably secured at spaced 90 points to the lining sheet to provide a loop 17 therein extending across the respective slits 8. One end of each of the cords 16 is adapted to be tied to one of the loops 15 on the upper edge of the blanket 10. 95

To the outer wall of the blanket 10 and approximately midway between its ends, spaced loops 18 are secured, and to these loops the inelastic tapes 19 extend. One portion of each of the tapes also extends 100 through a loop 20 which is secured to the inner side of the cover or case 7 adjacent the upper end thereof. The two portions of the tapes 19 are extended through the slits 8, one portion of the tape also extending 105 through the cord loop 17. As indicated, four of these inelastic tapes are employed, and one terminal of each tape is permanently secured to the end of an elastic suspender strap 21 while the other end of the 110

tape is adjustably and detachably connected to said strap by a suitable buckle indicated at 22.

In the use of the device, it will be understood, from reference to Fig. 1, that the same is drawn upwardly over the legs and upon the thighs of the user, the draw string in the upper edge of the case or cover 7 being tied around the waist in the usual manner. When applied to children, the device may be drawn upwardly above the hips and the outer string tied around the neck. For use upon adults, however, the elastic suspender straps may be employed, preferably in addition to the tie string, and will permit of the free movement of the legs in walking. The opposed portions of the blanket 10 at its lower edge are fastened together between the legs by means of the fasteners 12 so as to prevent the upward passage of cold air drafts. The front and rear portions of the outer case 7, at its lower end, may also be connected together at the inner sides of the legs by means of the fasteners 13. It will be understood that the device can be used either with or without water bottles or other heating means in the pockets 6 of the inner lining sheet. For use upon invalids, who are confined to their beds, the suspender straps may, of course, be entirely dispensed with.

From the foregoing description, taken in connection with the accompanying drawing, the construction, manner of use and several advantages of the invention will be clearly and fully understood. The device can be very easily and quickly applied to or removed from the limbs or body of the wearer and will afford complete protection against cold air drafts or low temperatures. The device will be found to be very serviceable and convenient by those persons whose blood circulation is below normal. The blanket can be easily and quickly removed by simply untying the strings 16 so that the inner lining sheet and the case or cover can be thoroughly washed and cleaned. It will, of course, be apparent that the article can be constructed in various sizes and any desired materials may be employed in the making of its several parts.

While I have herein shown and described the preferred construction and arrangement of the several elements, it is to be borne in mind that the same are susceptible of considerable modification and I, therefore, reserve the privilege of adopting all such legitimate changes as may be fairly embodied within the spirit and scope of the invention as claimed.

Having thus fully described my invention, what I desire to claim and secure by Letters Patent is:

1. An article of the character described including a blanket of tubular form, an

inner lining sheet for said blanket, an outer casing or cover for the blanket, and means for detachably connecting the blanket at one of its ends to said lining sheet.

2. An article of the character described including a blanket of tubular form, an inner lining sheet for said blanket, an outer casing or cover for the blanket, said lining sheet and the cover sheet being permanently secured to each other at one of their ends, and means for detachably connecting the blanket at one of its ends to said lining sheet.

3. An article of the character described including a blanket of tubular form, an inner lining sheet for said blanket, an outer casing or cover for the blanket, said lining sheet and the cover sheet being permanently secured to each other at one of their ends, means for detachably connecting the blanket at one of its ends to said lining sheet, and a draw string in one edge of the cover sheet.

4. An article of the character described including a blanket of tubular form, an inner lining sheet for said blanket, an outer casing or cover for the blanket, said lining sheet and the cover sheet being permanently secured to each other at one of their ends, means for detachably connecting the blanket at one of its ends to said lining sheet, a draw string in one edge of the cover sheet, and means connected to the blanket to suspend the same from the shoulders of the user.

5. An article of the character described including a tubular blanket, an inner lining sheet therefor having pockets to receive a suitable heating means, an outer casing or cover sheet for the blanket permanently secured at one of its ends to the lining sheet, and means for detachably connecting the corresponding end of the blanket to the lining sheet.

6. An article of the character described including a tubular blanket, an inner lining sheet therefor, an outer casing or cover sheet for the blanket permanently secured at one of its ends to the lining sheet, means for detachably connecting the corresponding end of the blanket to the lining sheet, and means for retaining the article in applied position upon the body of the user.

7. An article of the character described including a tubular blanket, an inner lining sheet therefor, an outer casing or cover sheet for the blanket permanently secured at one of its ends to the lining sheet, means for partially closing one end of the blanket, means for detachably connecting the other end of the blanket to the connected ends of the lining and cover sheets, and means for securing the latter end of the device around the waist of the user.

8. An article of the character described including an underskirt, an inner lining

sheet therefor secured at one of its ends to the wall of the underskirt, a blanket interposed between the wall of the skirt and the lining sheet, and means for suspending the 5 blanket from the shoulders of the wearer.

9. An article of the character described including an underskirt, an inner lining sheet therefor secured at one of its ends to the wall of the underskirt, a blanket interposed between the wall of the skirt and the lining sheet, means for partially closing one 10 end of the blanket, and means for suspending the blanket from the shoulders of the wearer.

15 10. An article of the character described including an underskirt, an inner lining

sheet therefor secured at one of its ends to the wall of the underskirt, a blanket interposed between the wall of the skirt and the lining sheet, means for closing the lower end 20 of the underskirt below the blanket around the thighs of the wearer, and means for suspending the blanket from the shoulders of the wearer.

In testimony whereof I hereunto affix 25 my signature in the presence of two witnesses.

DOROTHEA W. SCHWIEGER.
